UNITED STATES PATENT OFFICE

2,147,212

WINDING MACHINE

Edward F. Parks, Providence, R. I., assignor to
 Universal Winding Company, Boston, Mass., a
 corporation of Massachusetts

Application July 31, 1936, Serial No. 93,686

15 Claims. (Cl. 242—43)

The present invention relates to improvements in winding machines of a type such as illustrated and described in United States Letters Patent to Reece, No. 1,749,355, issued March 4, 1930; and more particularly to means for adapting a machine of this type embodying a rotary traverse-roll for winding packages of different lengths or for simultaneously winding a plurality of packages of less length than the full traverse of the roll.

One of the objects of the present invention is to provide a winding machine of the type indicated having means for reversing the direction of traverse of the yarn intermediate the ends of the traverse-roll.

Another object of the invention is to provide a winding machine of the type indicated in which a single traverse-roll is adapted to simultaneously traverse multiple yarns to wind a plurality of packages.

Another object of the invention is to provide a winding machine of the type indicated having adjustable means for reversing the direction of traverse of the yarn in either direction at any of the plurality of crossings of the oppositely extending helical yarn paths on the traverse-roll by which the yarn is guided.

Still another object of the invention is to provide in a winding machine adjustable means for reversing the direction of traverse of the yarn which is simple in structure and arrangement, efficient and positive in performing its intended function, and adapted to be applied to standard types of winding machines without alteration in the structure thereof.

Further objects of the invention are set forth in the following specification which describes a preferred form of construction of the device, by way of example, as illustrated by the accompanying drawings. In the drawings:

Fig. 1 is a transverse sectional view of a portion of a multiple winding machine showing one winding unit of a series incorporating the novel features of the present invention;

Fig. 2 is a front elevational view of the winding unit illustrated in Fig. 1 showing the adjustable means for reversing the direction of traverse of the yarn intermediate the ends of the traverse-roll;

Fig. 3 is a view similar to Fig. 2 showing a modified arrangement of the device with plural means for reversing the direction of traverse of a plurality of yarn supplies to simultaneously wind two packages from a single traverse-roll; and

Fig. 4 is a view similar to Figs. 2 and 3 showing another modified arrangement of the traverse-reversing means for simultaneously winding three separate packages.

Winding machines of the type illustrated and described in the Reece patent, referred to above, have gone into extensive use because of the increased speed at which the yarn can be wound and the facility with which the machine may be operated. In machines of this type a rotary 10 roll having continuous or interrupted grooves, ribs or other like helical guiding means on its periphery continuously traverses the yarn back and forth on the package in oppositely directed helical paths with the direction of traverse reversed at either end of the roll. Each roll is thus adapted to wind a single package of predetermined length.

The present invention relates generally to a stop or abutment mounted opposite the traverse-roll, and preferably adjustable longitudinally with respect thereto, to adapt it to cooperate with the helical guiding means of the roll to control the extent of traverse of the yarn thereby. The yarn engages the stop to reverse its direction of traverse intermediate the ends of the traverse-roll. Either one stop may be employed to wind a single package of predetermined length less than that of the traverse-roll; or a plurality of stops may be provided for winding several 30 packages from a plurality of supplies. The stops are preferably so constructed and arranged as to permit them to be slid along their fixed support to an operative position and fastened in place, or to be moved to an inoperative position 35 outwardly beyond the ends of the traverse-roll.

Referring to the drawings, the winding machine herein illustrated, by way of example, is of the double gang type comprising a plurality of winding units arranged in series along the opposite sides of a horizontal frame or bed 2 supported at its opposite ends by suitable legs, not herein shown. Spaced along the top of the bed 2 are a series of uprights 4 which mount bearings 5 for the driving shafts and other parts 40 of the winding mechanism, two opposite units being located between each pair of brackets, but only one unit being herein shown.

The winding mechanism of each unit comprises two principal elements, namely, the wind-mandrel or spindle 8 on which the yarn-receiver or cop-tube C is rotatably supported; and the roll 11 for rotating the yarn-receiver and in which is embodied the means for traversing the yarn back and forth axially of the pack- 55

age being wound. In this form of construction the usual reciprocating thread-guide is dispensed with, the roll 11 having its peripheral surface provided with a helical groove or grooves 12 and 13 extending in opposite directions and adapted to receive the strand of yarn to guide it back and forth between the ends of the package. The particular form of traversing means as herein shown is illustrated and described in the Reece patent, referred to above. It is to be understood, however, that the present invention is adapted for use with other forms of traversing rolls incorporating a similar principal of operation and having either interrupted grooves or projecting ribs which direct the yarn in its helical path; or with machines wherein the package is driven by contact with a drive-roll and the yarn traversed by a separate traverse-roll; or with machines having any other suitable arrangement of the winding elements.

The term "traverse-roll" as hereinafter used in the specification and claims is thus intended to include any type of roll or drum for traversing the yarn back and forth on the package, whether employed as a separate element or constituting the drive-roll as herein illustrated.

In the form of construction shown in the present drawings the roll 11 is carried on and rotated by a horizontal shaft 14 journaled in the bearings 5 on the uprights 4; the shaft 14 being extended throughout the whole length of the gang machine to carry a plurality of rolls for any desired number of winding units. It will be understood that in the preferred form of the machine a second parallel shaft, not herein shown, is journaled in bearings in the uprights 4 at the opposite side of the machine and carries another series of rolls.

The present machine is shown as adapted for winding packages of cylindrical form with the yarn built up on a suitable axial core or receiver, a paper or fiber cop-tube C for this purpose being illustrated in the drawings as mounted to rotate on the winding-spindle or mandrel 8. In other instances, however, the package may take the form of a truncated cone and in such case the traverse-roll may be correspondingly shaped. A suitable cop-holder 10, herein shown as comprising a cylindrical sleeve, is rotatably mounted on the spindle 8, being provided with any usual means for gripping the cop-tube C thereto. In other instances the holder may be of tapered form to adapt it to receive conical tubes.

The winding-spindle 8 is swiveled at the forward end of a weighted arm 16 which is pivotally supported at its rearward end on a horizontal rod 17 to adapt the surface of the yarn-receiver C, and the periphery of the package P, to be held in contact with the periphery of the roll 11. As the yarn is built up on the cop-tube C it forces the latter upwardly with the arm 16 swinging to machine of the present type. Although not herein shown in detail, a suitable stopping mechanism is employed with each unit of the machine to automatically arrest the winding operation by raising the package away from the roll 11. The stopping mechanism is controlled by a pivoted wire lever 18 held in inoperative position by the yarn being wound.

A tension-device 19 mounted on a bracket 20 is located intermediate the ends of the traverse-roll 11 and positioned at a distance outwardly and downwardly therefrom. The tension-device 19 is preferably of the self-threading type com-

prising a pair of rotatable tension-disks 21. Wire threading bails 22 and 23 are so shaped that a yarn drawn thereacross will be automatically guided into an eye 24 in the bail 22 and between the tension-disks 21.

In accordance with the embodiment of the invention illustrated in Figs. 1 and 2 of the drawings, a single stop or abutment 30 is adjustably mounted closely adjacent the traverse-roll 11 to adapt it to engage the traversing yarn to reverse its direction of traverse at any one of the plurality of crossings of the helical paths through which the strand is guided. The stop 30 may take any suitable form or shape, being herein illustrated as a cylindrical post or pin with a smooth rounded surface for engaging the yarn. The stop 30 may be mounted on any suitable support which may constitute a standard part of the machine or be applied thereto as an attachment. As herein illustrated, the stop 30 is mounted on a horizontally-extending support 31 which is in the form of a rod having its opposite ends held in sheet-metal clamps 33 fastened to the uprights 4 by screws 34. The clamps 33 are bent around to embrace the ends of the rod 31 which are clamped therein by means of bolts 35. The stop 30 has a transverse bore 36 through which the supporting rod 31 extends to mount the stop for adjustment longitudinally of the traverse-roll 11. An axial, threaded bore 37 is also provided in the stop 30 for receiving a set-screw 38 which is set up against the rod 31 to clamp the stop in adjusted position thereon. By loosening the set-screw 38 the stop 30 may be moved along the supporting rod 31 to any desired operative position intermediate the ends of the roll 11; or to an inoperative position outwardly beyond the ends thereof. One form of the invention having now been described in detail, its mode of operation will be next explained.

The strand of yarn y is drawn off from a bobbin or other source of supply, not herein shown, laid across the threading ball 22, the rod 31 and roll 11, and its end secured to the cop-tube C. If a package of standard length is to be wound a cop-tube C of a length substantially equal to that of the roll 11 is applied to the holder 10 on the winding-spindle 8 at the end of the arm 16. The arm 16 is then lowered into position to place the surface of the cop-tube C against the roll 11. The roll 11 is rotated continuously and the cop-tube C rotated therefrom to wind the yarn onto its periphery. As the yarn y is drawn across the threading ball 22 it is caused to automatically enter the eye 24 and between the tension-disks 21 to both guide and tension the strand as it leads to the roll 11. As the yarn draws across the rod 31 it is picked up by the groove 12 or 13, or such other means as provided on the periphery of the roll 11, to traverse it back and forth along the tube C to commence the winding of the package.

To adapt the machine to wind packages of a length shorter than that for which the standard roll is designed, a spindle and cop-tube holder of appropriate length are substituted for the standard spindle and holder. The stop 30 is then adjusted on the supporting rod 31 to a position slightly in advance of a particular intersection x of the oppositely directed helical yarn paths on the roll 11, being spaced from the terminus of the grooves in the roll a distance corresponding to the length of the package to be wound. To accomplish this adjustment the set-screw 38 is loosened to permit the stop 30 to

be slid along the rod 31 to its predetermined position and the set-screw then tightened to clamp the stop fixedly in place. Preferably, the angular position of the stop 30 should be such that the stop will extend outwardly from the rod 31 at right-angles to the direction of feed of the yarn.

With the roll 11 rotating in a counterclockwise direction, as viewed in Fig. 1, the groove 13 causes the yarn y to be traversed from the right-hand end of the roll toward the left until it engages the stop 30 as indicated by the dot-and-dash lines in Fig. 2. As a result of this engagement the yarn y is restrained from further traverse to the left and the length of yarn extending between the stop 30 and roll 11 is deflected to the right as it reaches the crossing x of the grooves 12 and 13, thereby causing it to be diverted into the return groove 12. The yarn y is then traversed toward the right-hand end of the traverse-roll to the position indicated by dash lines in Fig. 2 where its direction is again reversed as it again enters the groove 13. The yarn y is thus traversed back and forth throughout a portion only of the length of the roll 11 to build a package P of a length less than that of the roll. Fig. 2 illustrates the machine as adapted for building a package P of approximately two-thirds the length of the roll 11; but it will be understood that packages of several other lengths may be wound with the type of roll here shown by adjusting the stop 30 to a position slightly in advance of any one of the five crossings of the oppositely directed helical paths formed by the grooves 12 and 13.

If the yarn y breaks or becomes exhausted during the winding of a package, and when a full package P has been completed, the stopping mechanism acts to lift the arm 16 to move the package away from the roll 11. The break in the yarn y may then be repaired, or the completed package doffed and the machine prepared for a subsequent winding operation. The stop 30 is preferably made of such length that when the arm 16 is lifted to its uppermost position the yarn y will still be in engagement with the stop as indicated by dash lines in Fig. 1.

In the embodiment of the invention illustrated in Fig. 3 of the drawings, a pair of stops 30 are mounted on the supporting rod 31 to adapt them to function for reversing the direction of traverse of a plurality of yarn strands y' and y^2 intermediate the ends of the roll 11 to simultaneously wind two packages P' and P^2 . As herein shown the stops 30 are positioned at the longitudinal center of the roll and in abutting relationship. Two yarn strands y' and y^2 are fed from independent sources to lead across the rod 31 on opposite sides of the pair of stops 30 with their ends attached either to a single cop-tube or a pair of tubes C', in the usual manner. As the roll 11 is rotated the separate strands y' and y^2 feed through the traversing grooves 12 and 13 at the opposite ends of the roll, as indicated by dash lines in Fig. 3, and are caused to be traversed toward the center of the roll until they engage the stops 30. As explained with respect to the first form of construction illustrated in Figs. 1 and 2, the lengths of yarn between the stops 30 and the roll 11 are deflected as they approach the center crossing x' of the oppositely directed helical guiding paths which causes them to be diverted into the opposite grooves to reverse their direction of traverse. It will be understood that with the last described arrange-

ment the stops 30 may be adjusted to a position in conjunction with any of the other crossings of the oppositely directed helical yarn paths to wind packages of lesser length in spaced-apart relationship on the spindle 8.

In the embodiment of the invention illustrated in Fig. 4 of the drawings, two pairs of stops 30 are mounted on the supporting rod 31 to adapt the machine to wind three separate packages in spaced relationship on the spindle 8; one package being wound at the center of the roll 11 between the pairs of stops and the other two at the opposite ends of the roll. In this form of construction the grooves 12 and 13 on the roll 11 have a greater number of crossings and the stops 30 of one pair are adjusted to a position opposite the crossings x^2 and x^3 toward the left-hand end of the roll while those of the opposite pair are positioned opposite the crossings x^4 and x^5 toward the right-hand end of the roll. Yarn strands y' and y^2 from independent sources are fed across the rod 31 through the grooves 12 and 13 at the opposite ends of the roll 11, and a third strand y^3 is fed between the inner stops of the opposite pairs. Rotation of the roll 11 causes the yarn strands y' and y^2 to be traversed from the outer ends of the roll 11 toward its center until they engage the outermost stops 30 of each pair and their direction of traverse is then reversed as explained with respect to Fig. 3. The yarn strand y^3 is traversed in the groove 12 from the crossing x^3 toward the crossing x^4 until it engages the inner stop 30 of the right-hand pair which causes it to be diverted into the groove 13 to reverse its direction of traverse. The yarn y^3 is then traversed by the groove 13 in the opposite direction, or toward the left, until it engages the inner stop 30 of the left-hand pair which in turn causes it to be diverted to the opposite groove 12. It will also be understood that packages of still different dimensions may be wound on the machine by adjusting the stops to other positions.

It will be observed from the foregoing that the present invention provides a novel and simple arrangement of means for reversing the direction of traverse of the yarn intermediate the ends of a rotary traverse-roll to adapt the machine for winding single packages of different lengths or a plurality of packages of a predetermined length.

While I have herein described and illustrated several forms of construction of the device, by way of example, it is to be understood that modifications may be made in the structure and arrangement of the parts thereof without departing from the spirit or scope of the invention. Therefore, without limiting myself in this respect, I claim:

1. In a winding machine, means for supporting a package, means for rotating the package, means for traversing yarn to wind it in helical coils on the package, and stationary means for engaging the yarn to limit its extent of traverse to wind packages of less length than that of the full traverse.

2. In a winding machine, means for supporting a package, means for rotating the package, a rotary roll having means on its periphery for traversing yarn in opposite directions to wind it on the package, and stationary means for engaging the yarn intermediate the ends of the traverse-roll to reverse its direction of traverse.

3. In a winding machine, means for supporting a package, means for rotating the package, a

5 rotary roll having means on its periphery for traversing yarn in opposite directions to wind it on the package, and a normally stationary stop so related to the roll as to be engaged by the yarn to reverse its direction of traverse intermediate the ends of the roll, said stop being adjustable longitudinally of the roll to control the length of the wound package.

4. In a winding machine, means for supporting 10 a package, a drive-roll for rotating the package, said drive-roll having means for traversing yarn in opposite directions to wind it in helical paths on the package, and stationary means adapted to be engaged by the yarn and so related 15 to the roll as to reverse the direction of traverse of the yarn at one of the crossings of the oppositely directed helical paths.

5. In a winding machine, means for supporting 20 a package, means for rotating the package, a rotary roll having means on its periphery for traversing yarn in opposite directions, said traverse-roll normally acting to traverse the yarn throughout substantially the full length of the roll, and stationary means so related to the traverse-roll as to be engaged by the yarn to reverse 25 its direction of traverse intermediate the ends of the traverse-roll, said yarn reversing means being adjustable longitudinally of the traverse-roll to adapt the machine to wind packages of 30 different lengths.

6. In a winding machine, means for supporting 35 a package, means for rotating the package, a traverse-roll having means on its periphery for guiding the yarn in opposite directions in crossing helical paths, a fixed support extending longitudinally of the roll adjacent thereto, and a stop adjustable longitudinally of the support to a position intermediate the ends of the traverse-roll, said stop being adapted to be engaged by 40 the yarn to reverse its direction of traverse at one of the crossings in the oppositely extending helical paths whereby packages of different lengths may be wound on the same machine.

7. In a winding machine, means for supporting 45 a package, a drive-roll for rotating the package, said drive-roll embodying means for traversing yarn in opposite directions in crossing helical paths, a rod extending longitudinally of the roll in spaced relation thereto, and a stop 50 adjustable longitudinally of the rod to position it between any two of the adjacent crossings of the oppositely extending helical paths intermediate the ends of the drive-roll, said stop being adapted to be engaged by the yarn to reverse 55 its direction of traverse at an adjacent crossing whereby to effect the winding of packages of different lengths.

8. In a winding machine, means for supporting 60 a plurality of packages, means for rotating the packages, a traverse-roll having means on its periphery for guiding the yarn in opposite directions in crossing helical paths, a plurality of yarn supplies, and an abutment positioned adjacent the traverse-roll intermediate its ends to adapt 65 it to be engaged by the plurality of yarn strands to reverse their direction of traverse whereby the plurality of packages may be wound simultaneously with a single traverse-roll.

9. In a winding machine, means for supporting 70 a plurality of packages, a drive-roll for rotating the packages, said drive-roll having grooves on its periphery for traversing the yarn in opposite directions in crossing helical paths, a plurality of yarn supplies, and stops so related to the drive-

roll as to be engaged by the yarn strands from the several supplies to reverse their direction of traverse at a plurality of intersections of the helical paths intermediate the ends of the roll whereby the plurality of packages may be wound simultaneously with a single drive-roll. 5

10. In a winding machine, means for supporting a package, means for rotating the package, a rotary roll having means on its periphery for traversing yarn in opposite directions to wind 10 it on the package in helical coils, fixed guiding means positioned intermediate the ends of the roll at a distance therefrom, and a stop between the fixed guiding means and the roll and intermediate the ends of the latter, said stop being adapted 15 to engage the yarn to reverse its direction of traverse at a point intermediate the ends of the roll.

11. In a winding machine, means for supporting 20 a plurality of packages, means for rotating the packages, a rotary roll having means for traversing yarn in opposite directions to wind it in helical coils on the packages, two independent sources of yarn supply, and stops adjacent the periphery of the roll at its mid point for engaging 25 the two strands of yarn to reverse their direction of traverse whereby two packages may be wound simultaneously with a single traverse-roll.

12. In a winding machine, means for supporting 30 a plurality of packages, means for rotating the packages, a rotary roll having means for traversing 35 yarn in opposite directions in helical coils on the packages, a plurality of sources of yarn, and two pairs of stops arranged adjacent to and in spaced relationship longitudinally of the roll to adapt them to be engaged by the yarn strands to reverse their direction of traverse whereby a plurality of packages may be wound simultaneously with a single traverse-roll.

13. In a winding machine, means for supporting 40 a package, means for rotating the package, means for traversing yarn to wind it on the package, an abutment adapted to be engaged by the yarn to limit the extent of its traverse to wind packages of less length than that of the full traverse, and means for adjusting the abutment to different positions with respect to the traversing means to regulate the length of the package being wound. 45

14. In a winding machine, means for supporting 50 a package, means for rotating the package, a rotary element having grooves on its periphery for traversing yarn in crossing helical paths on the package, means in the roll for controlling the yarn at the points of crossing to prevent reversing 55 the direction of its traverse, and means adapted to be engaged by the yarn to nullify the effect of said controlling means whereby to cause the direction of traverse of the yarn to be reversed at a crossing point intermediate the ends of its full 60 traverse.

15. In a winding machine, means for supporting 65 a package, means for rotating the package, a rotary element having grooves on its peripheral surface for guiding the yarn to traverse it on the package, said grooves extending helically in opposite directions to cross each other and so formed as to prevent the yarn from being diverted from the path in which it is traveling and its direction reversed at a crossing, and means so related to 70 the rotary element as to engage the yarn to reverse its direction of traverse intermediate the ends of the rotary element.

EDWARD F. PARKS.
